UNITED STATES PATENT OFFICE.

WILLIAM S. GOEMBEL, OF GENESEO, ILLINOIS.

CULTIVATOR.

SPECIFICATION forming part of Letters Patent No. 453,183, dated June 2, 1891.

Application filed October 7, 1889. Serial No. 326,296. (No model.)

To all whom it may concern:

Be it known that I, WILLIAM S. GOEMBEL, a citizen of the United States, residing at Geneseo, county of Henry, State of Illinois, have invented a certain new and useful Improvement in Cultivators; and I declare the following to be a full, clear, and exact description of the invention, such as will enable others skilled in the art to which it pertains to make and use the same, reference being had to the accompanying drawings, which form a part of this specification.

My invention relates to certain improvements in connection with rotary disk cultivators; and the several improvements consist of a combination of devices and appliances hereinafter described and claimed.

In the drawings, Figure 1 is a rear elevation of my cultivator. Fig. 2 is a plan view. Fig. 3 is a side elevation with parts removed. Fig. 4 is a detail view of the shield. Fig. 5 is a detail view of the shield-frame. Figs. 6, 7, and 8 are views of the covering used on the shield. Fig. 9 is a side elevation of the disk. Fig. 10 shows the manner of attaching the disk to the standard. Figs. 11, 12, and 13 are views of the standard and the parts used to attach the disk.

In carrying out my invention, A represents the main axle, composed either of wood or iron, or both, and having the iron spindles B attached to the ends. Of course, if desired, the axle and spindles might be of one piece; but I prefer the construction shown.

C are the wheels, and D the main frame. The latter may be either wood or iron, as desired.

E E' are ratchets secured on both sides of the frame, and pivoted thereto are the levers F F'. These levers are connected by the chains G G' with the disk-beams Q, whereby the latter may be raised and lowered at will.

H represents the operator's seat supported by the bars I, which extend forward and are pivoted at i, these bars resting in the rests J J', attached to the axle; or, if the operator desires, he may transfer his weight to the cultivator-disks. This is done by the means of the forked standard K, which, being attached to the cultivator-beams at k, extends up adjacent to the bars I, where it is provided with the bolt k' and spring k². Thus by raising the

seat and allowing it to bear on the spring k² by the bolt k' the weight of the operator is transferred to the disk-beams.

L L' are arches connecting the disk-beams on either side and made adjustable by dividing them and attaching them together by bolts l. By providing a series of bolt-orifices the arches may be lengthened or shortened at will.

M are boxes attached to the disk-beams, and in these boxes are held the standards N by the bolts m. The standards are preferably shaped as shown in Fig. 10, with a journal-bearing n at the lower end. Through this bearing is passed the spool O, to which the disks P are attached by the bolts p, the end o' of the spool being squared and entering the square orifice in the disk. These bolts p extend from the disks, where they are held by the washer O', as in Fig. 12, through the spool and journal-bearing and secured by the nut p'. Thus the spool, with its disk, is free to revolve in the journal-bearing n.

It will be observed that the disks P are capable of being turned and secured in any desired position on these standards N. For instance, in Figs. 1 and 2 are shown the two forward disks facing outwardly, while the rest of them face inwardly. This arrangement is the preferred one, as it accomplishes a more thorough breaking up of the soil.

R is a shield supported between the disks by the rods R' and chain R². The front half of the shield is imperforate, made so by covering Z, as shown in Figs. 6, 7, and 8, and the rear portion is formed of slats or bars R³. The object of this shield is to protect young plants from being buried or injured, and yet allowing them by the soil working in small quantities through the bars R³ to cover them with enough new earth to facilitate growth.

S is a clevis attached to the middle of the axle, and the pole X is attached thereto. The draft is thus carried from the axle.

T is a lever pivoted to the pole in front of the frame and extending back adjacent to the seat, where it is provided with the handle t. Pivoted to this lever and extending on each side to the frame, where they are attached, are the rods T'. By means of the lever and its rigid connections it will be seen that a change of direction of the pole X or of the

rear end of the lever will correspondingly shift the line of travel of the cultivator-disks, and as the disks form the front bearing of the machine the direction of travel of the 5 whole apparatus may be thus directed.

U V are braces extending from the disk-beams to the main frame and supporting the former.

It will be observed that the upper end m' 10 of the standard where it enters the box M is made tapering, so that by means of the bolt m it can be drawn firmly to its seat, and yet by loosening the bolt the disk can be readily set at any angle. So, also, by making the 15 journal-bearing n at an acute angle, as shown in Fig. 10, the disk when placed in position will have the upper half of its concave face in line with the standard-bearing, while the lower half will be thrown out, as shown.

20. What I claim is—

1. In a cultivator, the combination, with the main frame, disk-beams and connecting mechanism, and the operator's seat, of braces extending from the disk-beams to the seat and 25 connected therewith by bolt k' and spring k^2 , substantially as described.

2. In a rotary disk cultivator, the combina-

tion, with the disk-beam and disk, of the standard connecting them, said standard having its journal-bearing for the disk inclined 30 upward and outward to throw the lower edge of the disk outward, substantially as described.

3. In a wheel-cultivator, the combination, 35 with the axle, the main frame, the disk-beams, and the pole pivoted to the axle, of a single lever pivoted to the pole in front of the frame and extending back adjacent to the seat, said lever rigidly connected between its forward and rear ends to the disk-beams, substantially as described.

4. In a rotary disk harrow, the combination, 40 with the frame and the double row of disks carried thereby, of an inverted U-shaped shield suspended between the two rows of disks, said shield formed with an imperforate forward portion and a slatted rear portion, substantially as described.

In testimony whereof I sign this specification in the presence of two witnesses.

WILLIAM S. GOEMBEL.
